(57) **CLAIM**

The ornamental design for a portable communications device, as shown and described.

DESCRIPTION

FIG. 1 is a front perspective view of the portable communications device with a camera in a closed configuration showing our design;

FIG. 2 is front view thereof;

FIG. 3 is a side view thereof;

FIG. 4 is an opposing side view thereof;

FIG. 5 is a rear view thereof;

FIG. 6 is an end view thereof;

FIG. 7 is an opposing end view thereof;

FIG. 8 is a front perspective view of the portable communications device in an open configuration;

FIG. 9 is a front view thereof;

FIG. 10 is a side view thereof;

FIG. 11 is an opposing side view thereof;

FIG. 12 is a rear view thereof;

FIG. 13 is a side and rear perspective view of a second embodiment of the portable communications device shown in FIGS. 1-12, the only difference over the first embodiment being that the replacement covers are shaded to indicate a contrasting surface treatment;

FIG. 14 is a side view thereof;

FIG. 15 is an opposing side view thereof; and,

FIG. 16 is a rear view thereof.

The broken lines shown herein are for illustrative purposes only and form no part of the claimed design. The stippled shading shown in the embodiment of FIG. 13 indicates an ornamental contrasting color or pattern. The illustrated device is not limited to the scale shown.
